UNITED STATES PATENT OFFICE.

JOSEPH M. MOHR, OF ELDORA, IOWA.

DOOR-OPERATING MECHANISM.

1,301,484.

Specification of Letters Patent. Patented Apr. 22, 1919.

Application filed August 9, 1918. Serial No. 249,154.

To all whom it may concern:

Be it known that I, JOSEPH M. MOHR, a citizen of the United States, residing at Eldora, in the county of Hardin and State 5 of Iowa, have invented new and useful Improvements in Door-Operating Mechanism, of which the following is a specification.

This invention relates to door opening and closing mechanism, the same being especially 10 designed for garage doors although not limited to doors of such structures.

The invention has for its object to provide a novel and improved electrically operated mechanism of the kind stated, the same embodying a motor which is operatively connected to the door, together with a controlling means to be hereinafter described in detail.

In order that the invention may be better 20 understood, reference is had to the accompanying drawings forming a part of this specification and in said drawings,

Figure 1 is a front elevation of a fragment of a double door showing the application 25 of the invention;

Fig. 2 is an elevation of the door operating mechanism viewed from the inside;

Fig. 3 is a plan view of said mechanism;

Fig. 4 is a view of a switch-actuating 30 mechanism;

Fig. 5 is an elevation of said mechanism;

Fig. 6 is an elevation of a supporting frame or bracket and certain gearing carried thereby;

Fig. 7 is a vertical section of the switch 35 actuating mechanism;

Fig. 8 is an elevation of a trip lever, and

Fig. 9 is an enlarged cross section on the line 8—8 of Fig. 7.

Referring specifically to the drawings, the 40 invention is shown applied to a double door, but it will be understood that it is also readily applicable to a single door. The two doors are indicated by the reference characters

10, they being hingedly connected to the doorway of the garage or other building structure, as shown at 10*. The means for swinging each door comprises a longitudinally movable rod or pitman 11 connected

45 at one end to the actuating means to be presently described, and at the other end to a crank arm 12 having a fixed connection with an upstanding pin 13 on a double acting spring hinge 14 fastened to the hinge end of

50 the door at the top thereof. It will therefore be seen that the door is swung open or closed

when the rod 11 is operated. Each door is provided with an operating rod 11, and as this rod operates the door by a movement in the direction of its length, the invention is 60 also applicable to a sliding door. The crank arm 12 is fastened to the pin 13 by a set screw 15, or any other suitable means.

At 16 is shown an electric motor supported by a suitable bracket 17 which is 65 mounted at any convenient place above the door-way in which doors 10 operate. On the shaft 18 of the motor is a worm wheel 19 which is in mesh with a worm 20 on a shaft 21. This shaft 21 also has a worm 70 wheel 22 which is in mesh with a worm 23 on a vertical shaft 24. On the lower end of the shaft 24 is made fast a crank arm 25 carrying a pin 26 to which one of the operating rods 11 is connected. Where two 75 doors are used, a second crank arm 27 will be provided for the operating rod of the other door, said arm being parallel to the arm 25 and connected thereto at the crank pin end thereof, with the operating rod connected to the opposite end. The two operating rods are therefore simultaneously actuated, their movement being in opposite directions.

The circuit of the motor 16 is controlled 85 by an ordinary snap switch 28 having a rotatable button 28* by which it is operated. The switch is carried by a bracket 29, supported by the bracket 17, and above the switch the bracket 29 has an outstanding 90 plate 29* which supports the switch-actuating mechanism. This mechanism comprises the following parts:

The plate 29* supports an upstanding sleeve 30 which serves as a support or bearing for a ratchet cylinder 31 having at its lower end a reduced and squared portion 31* by which it is attached to a spring clamp 32 which engages the switch button 28*, so that when the ratchet cylinder is given a turn, 100 the switch 28 is actuated.

The ratchet cylinder 31 is operated by two pawls, denoted by the reference characters 33 and 34, respectively. The pawl 33 is slidably mounted in a housing 33* carried by a 105 lever 35 fulcrumed on the sleeve 30. A spring 33* is connected to the pawl for advancing the same. In line with the pawl, 33, the sleeve 30 has a slot 30* through which the pawl passes into engagement with the 110 ratchet cylinder 31.

Above the lever arm 35, and spaced there-

from by a collar 36 encircling the sleeve 30, is a second lever arm 37 carrying a housing 34^a for the pawl 34, the spring of the latter being shown at 34^b. Here, the sleeve 30 is also slotted, as shown at 30^b to enable the pawl 34 to engage the ratchet cylinder 31. The collar 36 is split and left with an opening 36^a sufficiently wide to accommodate the inner end of the pawl housing 33^a, the collar 10 being loose on the sleeve 30 so that it turns thereon when the lever arm is swung. Above the lever 37 is a collar 38 similar to the collar 36, also loose on the ratchet cylinder, and provided with a slot to accommodate the inner end of the pawl housing 34^a. Above the collar 38 a collar 39 is fixed on the sleeve 30 by a cross pin 39^a or other suitable means, for retaining the two hereinbefore described lever arms and the parts associated therewith.

On the plate 29^a are two stop projections 40 between which the lever arm 35 swings, and which limit the swing of said arm.

To the lever arm 35 is connected a spring 41 which is arranged to swing it back to one of the stops and thus return it to normal position.

The ratchet cylinder 31 is also engageable by a spring pawl 42 for preventing its rotation in a reverse direction. This pawl is mounted in a housing 42^a carried by the bracket plate 29^a.

The lever arms 35 and 37 are provided with actuating means whereby they are operated independently, and one after the other. When the arm 35 is swung, the ratchet cylinder 31, through the pawl 33, is given a partial rotation to close the switch, after which the arm is swung back by the spring 41 to its normal position. The arm 37 is designed to open the switch. When this arm is swung, the ratchet cylinder 31, through the pawl 34, is given a further turn to open the switch.

The lever arm 35 is operated manually by means of a pull chain 43 connected to one of its outer ends. This pull chain passes through a tubular guide 43^a positioned above the doorway, and leading to any convenient point for actuation.

The lever arm 37 is operated automatically to open the switch and thus interrupt the operation of the motor after the doors 10 have opened or closed, this being accomplished by the following means.

On the bracket 17 is fulcrumed, as shown at 44, a lever 45 having one of its ends connected by a rod 46 to the lever 37, the connections being made by ball-and-socket joints 47. The other end of the lever 45 carries a cross piece 48 which is in the path of trip pins 49 and 50 carried by the crank arm 25 on opposite sides of the shaft 24. The lever 45 is also engaged by a spring 51, its swinging it in a direction opposite

to that in which it is swung by the trip pins 49 and 50.

In operation, when the switch 28 is closed by a pull on the chain 43, the motor 16 starts, and through the worm reducing gear hereinbefore described the crank arms 25 and 27 start to swing to open the doors 10 through the connections between the same and the crank arms. When the doors are wide open or nearly so, trip pin 49 strikes the end portion 48 of the lever 45 and swings said lever, whereby, through its connection 46 with the lever 37, and the ratchet mechanism, the switch is closed and the motor is stopped. To close the door, the chain 43 is again pulled to close the switch, and when the doors are closed or nearly so, the trip pin 50 comes into action to operate the lever 45 for opening the switch as before. The trip pins will be so positioned that the opening of the switch is properly timed.

By using a crank for operating the doors, they start to swing very slowly, the maximum speed being when they are half-way open or closed, after which they gradually slow down and come to a stop when fully open or closed. This gives the doors the most perfect movement in either direction, and eliminates jar and jerk due to a sudden starting or stopping. The double action spring hinges 14 enable the doors to be operated manually or by the mechanism described, without danger of breaking the actuating parts or putting the mechanism out of adjustment. It will be noted that the doors are opened and closed without reversing the motor. The doors are open after the crank arms 25 and 27 have made a half revolution, and they close as the crank arms swing to complete the revolution.

I claim:

1. In a door-operating mechanism, the combination with a movable door; of an electric-motor driven shaft, a crank arm on said shaft and having an operative connection with the door, a switch controlling the motor circuit, a ratchet member operatively connected to the switch, pawls engageable with the ratchet member for actuating the same, levers carrying the pawls, actuating means for one of the levers, a movable actuating member for the other lever, and trips on the aforesaid crank arm operating said actuating member after the switch has been closed.

2. In a door-operating mechanism, the combination with a movable door; of an electric-motor driven shaft having an operative connection with the door, a switch controlling the motor circuit, a ratchet member operatively connected to the switch, pawls engageable with the ratchet member for actuating the same, levers carrying the pawls, a manually operated actuating means for one of the levers, and means for actuat-

ing the other lever, said actuating means operating alternately.

3. In a door-operating mechanism, the combination with a movable door; of an electric-motor driven shaft, a crank arm on said shaft and having an operative connection with the door, a switch controlling the motor circuit, a ratchet member operatively connected to the switch, pawls engageable

with the ratchet member for actuating the same, levers carrying the pawls, actuating means for one of the levers, an actuating lever operatively connected to the other lever, and trips on the aforesaid crank arm operating said actuating lever after the switch has been closed.

In testimony whereof I affix my signature,
JOSEPH M. MOHR.
